DESIGN FOR A VACUUM TUBE

William W. Eitel and Jack A. McCullough, San Bruno, Calif., assignors to Eitel-McCullough, Inc., San Bruno, Calif., a corporation of California

Application October 10, 1941, Serial No. 103,705

Term of patent 14 years

(Cl. D26—8)

To all whom it may concern:

Be it known that we, William W. Eitel and Jack A. McCullough, citizens of the United States of America and residents of San Bruno, county of San Mateo, State of California, have invented a new, original, and ornamental Design for a Vacuum Tube, of which the following is a specification, reference being had to the accompanying drawing, forming part thereof.

Referring to the drawing, the figure of the

drawing is a perspective view of the vacuum tube, showing our new design.

The opposite side of the vacuum tube is substantially identical with that shown.

We claim:

The ornamental design for a vacuum tube, substantially as shown and described.

WILLIAM W. EITEL.
JACK A. McCULLOUGH.
